UNITED STATES PATENT OFFICE

140,598

DESIGN FOR AN ATOMIZER

Fred R. High, Attleboro, Mass., assignor to T. J. Holmes Co. Inc., Chartley, Mass., a corporation of Massachusetts

Application December 30, 1944, Serial No. 117,194

Term of patent 14 years

(Cl. D83—1)

To all whom it may concern:

Be it known that I, Fred R. High, a citizen of the United States, residing at Attleboro, in the county of Bristol and Commonwealth of Massachusetts, have invented a new, original, and ornamental Design for an atomizer, of which the following is a specification, reference being had to the accompanying drawing, forming a part thereof, in which

Figure 1 is a side elevational view of an atomizer, showing my new design;

Figure 2 is a top plan view thereof; and Figure 3 is a front elevational view thereof.

The essential features of my design reside in the portions shown in full lines in the drawing. The bulb shown in dotted lines in Figs. 1 and 2 is partially broken away for convenience of illustration.

I claim:

The ornamental design for an atomizer, substantially as shown and described.

FRED R. HIGH.
